UNITED STATES PATENT OFFICE

LESLIE H. L'HOLLIER, OF WALTHAM, MASSACHUSETTS, ASSIGNOR TO THE B. F. GOODRICH COMPANY, OF NEW YORK, N. Y., A CORPORATION OF NEW YORK

DESIGN FOR A SHOE SOLE

Application filed October 27, 1932. Serial No. 45,595. Term of patent 14 years.

To all whom it may concern:

Be it known that I, LESLIE H. L'HOLLIER, a citizen of the United States, residing at Waltham, in the county of Middlesex and Commonwealth of Massachusetts, have invented a new, original, and ornamental Design for a Shoe Sole, of which the following is a specification, reference being had to the accompanying drawing, forming a part thereof.

In the drawing, Fig. 1 is a plan view of a shoe sole embodying my new design, and

Fig. 2 is a longitudinal-sectional elevation on line 2—2 of Fig. 1.

I claim:

The ornamental design for a shoe sole as shown.

LESLIE H. L'HOLLIER,
